UNITED STATES PATENT OFFICE.

SAMUEL B. WILLIAMS, JR., OF BROOKLYN, NEW YORK, ASSIGNEE, BY MESNE ASSIGNMENTS, TO WESTERN ELECTRIC COMPANY, INCORPORATED, A CORPORATION OF NEW YORK.

AUTOMATIC TELEPHONE SYSTEM.

1,294,587.

Specification of Letters Patent. Patented Feb. 18, 1919.

Application filed August 25, 1914, Serial No. 858,481. Renewed January 23, 1917. Serial No. 144,059.

To all whom it may concern:

Be it known that I, SAMUEL B. WILLIAMS, Jr., a citizen of the United States, residing at Brooklyn, in the county of Kings and State of New York, have invented certain new and useful Improvements in Automatic Telephone Systems, of which the following is a full, clear, concise, and exact description.

This invention relates to automatic telephone systems, and more particularly to that part of a system by means of which a calling line is automatically selected and associated with the remainder of the office selecting apparatus.

In systems of the type toward which the present invention is particularly directed, a number of line finding and connecting circuits are provided for the common use of a larger number of telephone lines; and when any one of the telephone lines initiates a call, one or another of the line finding switches in which the finder circuits terminate is automatically made operative to connect with the calling line, the finder switch that is made operative being one that is at the time disengaged or idle. The principal object of this invention is to provide an improved control system for use in such an organization to insure one finder circuit, and one only, being made operative to connect with a calling line when a call is initiated; to prevent the finder circuit that is thus made operative from establishing connection with more than one line; and to simplify and improve the part of the organization which has to do with the preparing or assigning of the finder circuits and switches for serving the calling line.

Another object of the invention is to prevent a single line finding mechanism from searching for and establishing connection with two lines in different groups at the same time, when calls in different groups are initiated simultaneously, or practically simultaneously. In the particular embodiment in which the invention is illustrated, the finding switch is of the multiple brush type, that is of the type in which the movable element is provided with a plurality of brushes, one for each of the groups of lines served by the switch. The brushes are nor-

mally held in position not to engage their respective stationary terminals, and one or another brush or set of brushes, is tripped and made operative, depending upon the group in which the line that is to be engaged is located.

In automatic telephone systems of the type to which this invention relates, it is the practice to provide a plurality of extension circuits terminating upon line finder switches, all of which have access to the same group or groups of lines, so that the calling line may have its connection extended through the medium of any one of the finder switches that is not in use at the time. Still another object of this invention is to provide an organization in which the initiation of a call causes one and only one of the plurality of idle finder switches to become active to extend the connection of the calling line. When a subscriber calls, one of the finder switches that is not in use is made active through the medium of a starting circuit common to the finder switches and to the lines that they serve, and makes connection with the calling line. In its movement the finder switch that is selected places another finder switch in readiness to respond to the next call that is initiated. The calling condition of the line, which results in the starting of the finder switch, persists until the finder switch has connected with the calling line, which may be some time subsequent to the time when the next finder switch in order has been placed in operative relation with the starting circuit. To prevent the continuation of this calling condition of the line from causing the starting of the next finder switch in order, the system is so organized that the calling line is deprived of control over the starting circuit from the time the next finder switch has been placed in readiness until the started switch finds and alters the starting condition of the calling line.

A further object of this invention resides in the provision of means whereby when a call is initiated on one of the lines served by a group of finder switches, a tripping device will be actuated which is arranged to release any of the brushes of said switches

which have access to the calling line terminals and which are in normal position. Heretofore, in systems of this type, a tripping device has been employed for each switch, and it has been necessary to operate this device during a preliminary selecting movement of the switch in order to select and render operative the desired set of brushes. In the present system, the tripping devices are common to all the switches of a group, one tripping device being provided for all the brush sets having access to the same section of the panel bank. The particular tripping device for releasing the desired set of brushes is operated prior to the actuation of the switch. This allows selection to take place rapidly without the relatively long preliminary brush-selecting movement required by previous systems of this type.

It has been the usual practice in telephone systems to equip each subscriber's line with a line and cut-off relay. In a large exchange this equipment is very costly. Systems embodying this invention require only a few relays common to a group of lines, these relays being associated with a distributor or call finder which successively tests the lines of the group.

In the particular embodiment of the invention herein described, a distributor or call finder circuit, common to a group of telephone lines, picks up and records an incoming call. The record of this incoming call is registered in the line finder starting circuit, thereby starting a preselected line finder which will hunt for the terminals of the calling line. As soon as the line finder begins to hunt for the calling line terminals, the calling line record is obliterated by the release of the line finder starting apparatus.

In testing for the calling line terminals, the line finder hunts for the terminals of lines which have not been previously selected by some other finder switch or connected with another calling line, and tests the line terminals of such circuits for the calling line condition. When the calling line terminals are found, they are seized by the finder switch brushes, and the subscriber is then connected directly through the finder switch circuit to the telephone selecting apparatus at the office, by means of which any desired subscriber may be selected and called.

The invention is illustrated in the accompanying drawings in which—

Figure 1 is a front elevation, partly in section, of the distributor or call finder;

Fig. 2 is a side elevation on the line A—B of Fig. 1 of the distributor or call finder, the armature being shown partly in section;

Fig. 3 is a side elevation of the line finder switch structure;

Fig. 4 is a rear view of the commutator bar;

Fig. 5 is a plan view of a line finder brush, and shows a portion of the line finder terminal panel in section;

Fig. 6 shows a front view of the brush-tripping mechanism and two brush rods, one in its normal position and one slightly displaced from normal;

Fig. 7 is a view in perspective of the brush-tripping rod;

Fig. 8 is a side view of a section of the brush rod with the brush operating mechanism in its actuated position;

Fig. 9 shows the distributor and starting circuits;

Fig. 10, the line finder circuit; and

Fig. 11 is a schematic illustration of the line finder panel bank wiring with the brush-tripping and operating mechanism of several distributor circuits shown in perspective.

The distributor or call finder mechanism shown in Figs. 1 and 2, consists of a stationary drum 20 and a movable sleeve 21 mounted on the shaft 23. The shaft 23 is rigidly supported in the brackets 24 and 25. The stationary drum 20 is in effect a commutator consisting of the insulated portion 26, in which are mounted conducting segments such as 27, 28 and 29, which represent respectively the tip, ring and sleeve conductors of a line. All the lines, which are assigned to a particular distributor mechanism, appear as conducting segments in the periphery of this armature. These conducting segments are carried to the side of the distributor, where they end in terminals to which the line wires may be attached. Rigidly attached to the movable sleeve 21 is the gear wheel 22, the slip rings 35, 36 and 37, and the arm 33, to which are attached the brushes 30, 31 and 32. The slip rings are insulated from the sleeve 21 and from each other. By driving the gear wheel by any suitable means, the movable sleeve 21 will rotate about the shaft 23 and thus carry the brushes 30, 31 and 32 around the periphery of the armature. The brushes, when rotating in this manner, will make contact in rapid succession with the tip, ring and sleeve terminals of the lines assigned to this particular distributor, which appear as contact segments in this armature. The brushes 30, 31 and 32 are electrically connected to the slip rings 35, 36 and 37, and the brushes 40, 41 and 42 respectively cooperate with these slip rings. The terminal ends of the latter brushes are connected directly to the distributor circuit. It consequently follows that as the brushes 30, 31 and 32 rotate about the drum 20, the lines, which are assigned to the particular distributor, will be successively connected to these brushes, and from there, by means of the slip rings 35, 36 and 37 and the brushes 40, 41 and 42, to the distributor circuit.

The line finder switch structure, illustrated

in Fig. 3, is similar in operation to the one shown and described in United States Patent to John N. Reynolds, No. 1,103,623, with the exception of the method of tripping and actuating the brushes, which will be well understood from the following detailed description. A very brief description herein of the operation of the switch is consequently considered sufficient.

10 The motor elements of the switch consist of the two power-driven friction rollers 43 and 44, the first of which rotates in a clockwise direction to elevate the brush-rod, while roller 44 rotates in a counter-clockwise direction for returning the brush-rod to normal. The upward movement of the brush-rod is under the control of the electromagnet 45. When this magnet is energized it will attract its a. mature 46, which carries with it the bell 20 crank 47 which is pivoted at 48. Due to this movement of the bell crank 47, the idler pulley 50 is moved to the right and presses the elevating bar 51 against the power-friction roller 43. The elevating bar 51 contains a 25 series of notches, as described in the patent to Reynolds above referred to, which, in conjunction with the retaining pawl 52, maintain the brush-rod in its elevated position when the electromagnet 45 is deenergized, and the idler pulley 50 returns to its normal 30 position.

The electromagnet 53 controls the return movement of the brush-rod. The operation of this magnet, in a manner similar to that 35 described in connection with the magnet 45, presses the idler pulley 54 against the power-driven friction roller 44, and as this roller rotates in a counter-clockwise direction, the brush-rod will be returned to its normal 40 position. The movement of the bell crank 39, associated with the electromagnet 53, trips the retaining pawl 52 by means of the finger 55, which cooperates with the lower projection 56 of the retaining pawl 52.

45 At the uppermost portion of the switch is mounted a commutator bar 57. This bar is composed of insulating material, and on one side thereof are mounted the conducting segments K, X and Y. The brush 58 cooperates with the segments K and X, and the brush 59 with the segments Y and X. The commutator brushes 58 and 59 are rigidly attached to the brush-rod 60, and hence will be elevated and glide over the surface of the 50 commutator bar as the rod 60 is raised. The conducting strips K and X are so placed and proportioned that the brush 58, in its upward movement, closes contact with the strip K immediately after one of the line 55 finder brushes is tripped, and opens before this brush reaches the first line terminal in the panel bank. The brush 59 is in contact with the terminal strip Y when this brush is in its normal position, and the contact is broken before the tripped line finder brush

reaches the first terminal in the panel bank. The brushes 58 and 59 both make contact with the terminal strip X when the line finder brush leaves the uppermost terminal of the panel bank.

70 The reverse side of the commutator bar, as shown in Fig. 4, is equipped with the four insulated conducting segments 61, 62, 63 and 64. Cooperating with these conducting segments and in constant contact therewith are the brushes 65, 66, 67 and 68. The conducting segment 61 is grounded, while the segments 62, 63 and 64 are wired to the tip, ring and sleeve conductors respectively of the line finder circuit. The brush 65 is wired to the commutator brushes 58 and 59, while the brushes 66, 67 and 68 are wired in multiple to all the line finder brushes on the brush-rod of a particular line finder switch. The brushes 65, 66, 67 and 68 are likewise 85 rigidly connected to the brush-rod 60.

80 The terminal panel of each line finder switch is equipped with groups of terminals equal in number to the number of distributor circuits, which the line finder switch serves. 90 Each of these groups contains a tip, ring and sleeve terminal for each line connected to its individual distributor circuit. These terminals are grouped in a vertical row in front of the brushes of the line finder switch, and are 95 multiplied horizontally so as to appear in a similar manner in front of the brushes of other line finder switches. This wiring is shown schematically in Fig. 11, in which the cables 10, 11, 12 carry the multiple line connections from the distributor circuit to the line finder terminal panel. The position of the brush-rods of the various line finder switches is shown schematically by the vertical broken lines.

100 Associated with each group of terminals is a line finder brush, such as shown in Fig. 5. This brush consists of the springs 78, 79, 80 and 81, which are rigidly supported on a mounting block 82, which in turn is clamped to the brush-rod 60. Attached to these springs are the soldering terminals 97, 98 and 99, and the contact plates 70, 71, 72 and 73, which serve to contact with the terminals of the panel whenever the brush is released. 105 When the brush is in its normal position, as shown in Fig. 5, the contact plates do not connect with the line terminals of the bank. The brush is held in this position by the insulated rollers 76 and 77. These rollers hold 110 the springs 79 and 80 in tension, and prevent the contact plates 71 and 72 from connecting with the line terminals of the panel bank. Attached to the springs 78 and 81 are the insulating blocks 74 and 75, which ride on the outer surface of the springs 79 and 80, and which hold these springs in their normal position. Integral with the mounting block 82 is the bracket 91, which serves to carry the brush-tripping and resetting lever. 115 120 125 130

This brush-tripping and resetting lever consists of the cross-piece 93, on which are mounted the rollers 76 and 77, and integral with which are the downwardly extending fingers 94 and 95. The tripping and resetting lever is mounted in the bracket 91 by means of the pin 92. It follows, therefore, that if a pressure be exerted upon the finger 94 so as to move it in a downwardly direction, the rollers 76 and 77 will move out of the narrow inclosure formed by the springs 79 and 80, and the springs 78, 79, 80 and 81, due to their resilience, will move into contact with the line terminals of the panel bank. Likewise, if a pressure in an upward direction be exerted upon the finger 95, the rollers will be returned to their normal position, and the brush contacts will break the connection with the line terminals of the panel bank.

As previously stated and as shown conventionally in Fig. 11, a plurality of line finders are mounted in front of the panel terminal bank. At right angles to the line finder brush-rods and in front and below each group of line terminals, extends a common brush-tripping rod 83. The movement of this rod is controlled by the brush-tripping magnet 84. When this magnet is energized, it attracts its armature 85, which carries with it the connecting link 86. The connecting link 86 is pivoted to the lever 87 which is rigidly connected to the brush-rod 83. Consequently, whenever the armature 85 of the brush-tripping magnet is attracted, this movement will be transferred by means of the connecting link 86 and the lever 87 to the brush-tripping rod 83. When the brush-tripping magnet is deenergized, the brush-tripping rod will be returned to normal by means of a suitable spring.

Mounted on the brush-tripping rod are a plurality of tripping pawls 88, one for each brush of each line finder circuit. The pawl 88 is loosely connected to the rod 83. Associated with the pawl 88 and rigidly mounted on the rod 83 is tripping dog 89. A spring 90 is rigidly attached to the pawl 88 and to the brush-tripping rod 83. This spring holds the tripping pawl 88 against the tripping dog 89. The spring 90 is so tensioned that it will have sufficient power to trip the brush by means of the finger 94, and at the same time the spring connection is such that it will allow the finger 94 to pass by a tripped pawl 88, if, for any reason, the brush mechanism is out of adjustment and sticks. When the brush-rod is moved, due to the energization of the armature of magnet 84, the pawls 88 are displaced from normal in such a manner that their outer extremity comes within the path of the downwardly extending finger 94 of the brush-tripping mechanism. Consequently, when the brush-rod is moved in an upward direc-

tion, the arm 94 is tripped, moving the insulating pieces 76 and 77 to a position which will allow the contact plates of the brush to make contact with the terminals of the terminal bank of the line finder. When the brush-rod is returning to normal, the outer end of the finger 95 of a tripped brush will move in a plane containing the brush-tripping rod 83. Therefore, just before the tripping rod returns to normal, it will exert an upward pressure on the finger 95, which in turn will restore the brush to normal, as previously explained. Figs. 6 and 8 show the position of a brush just about to be restored to normal.

In practice the operation of the brush-tripping mechanism will preferably be as follows: When a brush-tripping magnet 84 is operated, it will turn the tripping rod 83 and thereby move the brush-tripping pawls 88 of all the line finders, associated with a particular group of line terminals, into the plane of the brush-tripping finger 94. A selected line finder will then start to elevate its brush-rod, and thereby trip a brush which will then hunt for the calling line. After the brush is tripped and before it reaches the first line terminal, the tripping magnet 84 is released and the brush-tripping rod restored to normal, at which time the remaining idle line finder circuits are again available for another incoming call.

The circuits of this system are illustrated in Figs. 9, 10 and 11. To simplify these drawings the distributor or call finder, associated with the circuits shown in Fig. 9, is shown in conventional form as a series of contact segments 27, 28 and 29, representing the tip, ring and sleeve conductors of the line, and a set of brushes 30, 31 and 32 coöperating with these segments.

Fig. 10 shows one complete line finder circuit and the selecting circuits for two additional line finders. The apparatus and connections for the two additional line finders are identical with that shown in the first line finder, but have been omitted to simplify the drawing. The controlling circuits, associated with the various parts of the line finder circuit which must be established in a definite order at successive stages of the operation of the system to bring the various parts into operation, as required, are established by automatic switching mechanisms which are called sequence switches. One of these sequence switches is associated with each line finder circuit. Each of these sequence switches consists briefly of a plurality of circuit-changing contacts adapted to be operated in a definite sequence. The particular structure is unimportant for the purposes of the present invention, but a satisfactory type is conventionally illustrated as consisting of a plurality of rotating disks or wipers,

which are represented in the drawing by a long contact. A plurality of springs or brushes are provided for engagement with each pair of conducting plates. In the following description of the system, the brushes or springs, which coöperate with each plate, will be referred to as contacts 1, 2, 3 and 4, representing respectively the upper left-hand, the upper right-hand, the lower left-hand and the lower right-hand contacts. By means of these brushes and a proper cutting away and arrangement of the conducting plates on the insulating disk, any two or more brushes arranged for engagement therewith may be electrically united at any stage of rotation of a shaft.

The sequence switch positions, at which the various springs or brushes are in engagement with the rotatable disk, are indicated by numerals placed adjacent to the several contacts respectively. Motor mechanism is provided for rotating the shaft in its successive step-by-step movement. These mechanisms, in the embodiment here-
25 in shown, comprise continuously rotating friction disks, such as shown at 101, 201 and 301. The rotatable shaft of each sequence switch is provided with a coöperating friction disk, such as shown at 102, 202 and 302, and an electromagnet is provided for causing effective engagement of the friction disks, whereby the switch shaft may be rotated. Each sequence switch is provided with a special contact A. The numerals appearing adjacent to this contact represent the only positions in which it is open, and consequently the only positions at which the sequence switch can stop.

The operation of the system will now be described in detail in connection with the circuit illustrations, Figs. 9, 10 and 11.

The call finder or distributor, which is shown conventionally in Fig. 1 is kept in continuous rotation, and consequently the brush 32 successively makes contact with the segments 29, connected to the sleeve circuit of the various lines, which appear as contact segments in the armature of the call finder. Due to this connection between the brush 32 and the contact segment 29, a circuit is closed from ground, through the resistance coil 121, the contact segment 29, the brush 32 and the relay 122, to battery. Consequently, this relay is intermittently energized as the brushes of the call finder sweep over the sleeve contact segments located in the armature. The attraction of the armatures of relay 122 connects the terminals of the line relay 123 with the tip and ring line segments of the various lines connected to the distributor armature. Therefore, if the subscriber has removed his receiver from the hook, a circuit will be completed when the brushes of the call finder make contact 85 with the tip and ring segments of the arm-

ture which are connected with the particular subscriber's line. This circuit may be traced from battery, through one winding of the line relay, armature 124 of relay 122, brush 30, segment 27, through the subscriber's loop, and back to segment 28, brush 31, contact and armature 125 of relay 122 and the second winding of the line relay, to ground. This will energize the line relay 123, which will attract its armature and close a circuit from ground by way of its armature and contact, through relay 126, to battery. This will operate relay 126, which will lock over a circuit which may be traced from ground, through the armature of relay 127 and armature 128, and the coil of relay 126, to battery. The attraction of armature 129 of relay 126 will complete a circuit from ground, through this armature and its contact, and the high-wound coil of relay 130, the armature 131, coil and armature 132 of relay 133, and thence by way of the armature 134 of relay 135 and the armature 136 of relay 137, to battery.

Connected in parallel with the coil of relay 133 and thus included in the circuit just traced, are the coils of the brush-tripping magnet 84. This circuit may be traced from the armature 132 of relay 133, through the coils of the tripping magnet 84, and back to the armature 131 of relay 133. The completion of this circuit will energize the relay 130. Relay 133 and the tripping magnet 84 will not be energized, however, because of the high-resistance of the winding 100 of relay 130. The attraction of the right-hand armature of relay 130 will close a circuit from ground, through the left low-wound coil of relay 130, to armature 131 of relay 133. This, in effect, replaces the ground which was originally supplied for attracting relay 130 through the high-wound right-hand winding, and as this high-wound winding is now shunted by the low-wound left-hand winding, the relay 133 and the brush-tripping magnet 84 will be energized and will attract their armatures.

The operation of relay 130 will likewise close a circuit from ground by way of the left-hand armature of this relay, through the winding of relay 127 to battery. This will energize relay 127 which will attract its armature, and open the locking circuit of relay 126, thus releasing this relay. The deenergization of relay 126, in conjunction with the operation of relay 133, will open the operating circuit of relay 130 which will be deenergized, and this in turn will deenergize the relay 127.

The operation of relay 133 will lock this relay over a circuit which can be traced from ground by way of armatures 140, 131 and the coil of relay 133, and thence by way of the armatures 132 and 141 of this relay, through the coil of relay 135 and armature 136.

136 of relay 137, to battery. This will permanently lock relays 135 and 133 until the locking circuit is broken at the armature 136 of relay 137. The attraction of the armature 134 of relay 135 will remove the battery connection from the multiple circuit to the armatures 132 of the relays 133 of the various line-finder starting circuits. This cuts off the electrical connection to the line-finder circuits from the various distributor circuits. The operation of this circuit will be explained more fully hereinafter.

The attraction of armature 142 of relay 135 closes a circuit from ground by way 15 of armature 142, through contacts 4 and 1 of sequence switch spring 103 and relay 143, to battery. It is assumed in this connection that the sequence switch of this first line-finder circuit has been preselected and is in 20 its second position, the method of preselecting to be explained later on. The closing of the circuit just traced will energize the relay 143, which will attract its armatures and close a circuit from ground, through 25 its left-hand armature and contact, contacts 4 and 3 of sequence switch spring 113, and thence through the operating magnet of the sequence switch 100, to battery; the relay 143 being locked in its operated 30 position by a circuit completed by the attraction of its right-hand armature. The sequence switch 100 will consequently move into its third position. In moving to its third position, a circuit will be closed mid-35 way between the second and third positions, from battery through the coils of the brush-elevating magnet 45, contacts 3 and 4 of sequence switch spring 104, the contact and right-hand armature of relay 143, contacts 40 2 and 3 of sequence switch spring 105, and armature 144 of relay 137 to ground. This will energize the elevating magnet 45, which in turn will force the idler pulley against the elevating bar 51, and the brush-45 rod will start to move upward toward the terminals of the first line in the panel bank. In this movement the finger 94 will be engaged by the tripping pawl 88, associated with the brush-rod of the energized tripping 50 magnet 84, and the brush will be tripped and moved so that the contacts 70, 71, 72 and 73 will connect with the line terminals of the bank when the brush reaches the position opposite to these terminals. Before 55 the brush reaches the terminals of the contact bank, a circuit will be closed from ground, through the commutator brush 58, contact segment K, contacts 3 and 2 of sequence switch spring 117, and thence 60 through the coil of the release relay 137, to battery, thereby energizing relay 137. This circuit just traced will be open at the commutator segment K before the sequence switch reaches its third position, and before

the brushes make contact with the first 65 group of line terminals of the terminal bank.

The operation of relay 137 attracts its armature 136, which opens the locking circuit previously traced containing relay 132, the coils of the brush-tripping magnet, and 70 relay 135, which will therefore be deenergized and restored to normal. The attraction of armature 144 of relay 137 opens a locking circuit containing the relay 143, which may be traced from battery, through 75 the coil of relay 143, the right-hand armature of this relay, contacts 2 and 3 of sequence switch spring 105, and the armature 144 of relay 137, to ground. Relay 143 will therefore be deenergized. When the circuit 80 containing relay 137 is opened at the commutator segment K, this relay will be deenergized, and its right-hand armature 144, in falling back to normal, will close a circuit from ground, through this armature, contacts 3 and 2 of sequence switch spring 105, the right-hand armature and back contact of relay 143, sequence switch contacts 2 and 2 of sequence switch spring 106, sequence switch contacts 3 and 2 of sequence switch 85 spring 215, and thence through the operating magnet of sequence switch 200, to battery. This will move the sequence switch 200 into its second or preselected position, ready to receive an incoming call from the 90 distributor and starting circuits which have now all been restored to normal.

In the third position of the line-finder sequence switch, the line-finder brushes will hunt for the terminals of the calling line. 100 In this operation the brushes make a double test, which consists primarily of a test of the sleeve conductor for a line condition, showing that the circuit that is being tested has not been connected to the terminals of any 105 other finder or connecting circuit, and secondarily tests the tip and ring conductors of the line for the calling line condition, that is, a closed subscriber's loop, caused by the removal of the receiver at the subscriber 110 station. The sleeve conductor of the brush, in testing the sleeve terminals of the line, closes a circuit from ground by way of the resistance coil 121 and the sleeve of the line to the sleeve terminal of the contact panel; 115 and thence by way of the sleeve brush, through contacts 1 and 4 of sequence switch spring 107, and through the relay 145 to battery. In case the line, with which this sleeve circuit is associated, has not been previously connected for use, the relay 145 will be energized and attract its armatures. The attraction of the armatures of this relay will close a circuit, provided the line that is being tested is a calling line, from battery, through the left-hand coil of relay 146, the inner armature and contact of relay 145, contacts 120 4 and 1 of sequence switch spring 108 to the 125

ring spring of the brush, and thence by way of the ring terminal of the contact panel out on the ring side of the line and back through the subscriber's station, the tip side 5 of the line, the tip terminal of the contact bank and the tip brush, the contacts 1 and 4 of sequence switch spring 109, the outer armature and contact of relay 145, and through the right-hand winding of relay 146 10 to ground.

If the line, that is being tested by the sleeve terminal, has been previously connected for service, the relay 145, included in the sleeve circuit, will not be energized 15 because it is shunted by the resistance coil 161 associated with the other finder circuit which is connected in multiple to this sleeve terminal. The relay 145 is so designed that it will not be energized in parallel with the 20 low-wound resistance coil 161. This sleeve shunt circuit, through the coil 161, is closed at contact 3 of sequence switch spring 107 in positions 3½ to 5 of the sequence switch, thus guarding the line during this interval. 25 The low-wound resistance 161 likewise shunts out the line sleeve relay 122, whenever the circuit through this relay is closed, as the rotating brush 29 of the call finder connects with the sleeve segment of a busy 30 line. This prevents the operation of this relay and the subsequent operation of the line relay 123, which in turn prevents the actuation of the apparatus in the line finder starting circuit. In this manner the unnecessary starting of line finders, by lines that 35 have been connected for service, is prevented.

Consequently, when the sleeve conductor of the line finder tests a sleeve terminal of a line which has been connected for service, 40 the relay 145, associated with its circuit, will not be operated, and consequently the relay 146 will not be connected to the line circuit and will not make a test of the tip and ring conductors of the line circuit. However, for 45 all circuits that have not been connected for service, the relay 145 will be energized, and thus as the brushes of the finder circuit move upward over the terminals of the contact bank, the relay will be intermittently operated and connect the secondary test relay 146 to the tip and ring terminals of the 50 various line circuits.

When the tip and ring terminals of the line circuit, associated with a calling subscriber's line are reached, the relay 146 will be energized, as previously explained. The operation of this relay closes a circuit from ground, through its armature and make contact, through the contacts 3 and 4 of sequence switch spring 110 and the operating magnet of the sequence switch 100, to battery. This will move the sequence switch 60 into its fourth position, which will deenergize relays 145 and 146.

The circuit arrangement illustrated in 65 Figs. 9 and 11 is so provided that a plurality of calls may be stored or recorded. When the brushes of the distributor switch encounter the terminals of a calling line, the relay 126 (see Fig. 9), is locked up subject to the control of the relay 127, thus recording 70 the call in the distributor circuit. If the starting circuit is free, the operated condition of the relay 126 leads to the locking up of the relays 133 and 135, subject to the 75 control of the relay 137, thus transferring the call to the starting circuit and recording it there. A finder switch being in operative relation with the starting circuit, the call recorded in the starting circuit starts that 80 finder switch. The transfer of the recorded call from the distributor circuit to the starting circuit frees the distributor circuit and makes it responsive to any other calling line the terminals of which are encountered. The 85 transfer of the recorded call in the starting circuit to the finder switch that is started, frees the starting circuit and makes it responsive to any other call which may in the meanwhile have been recorded in the distributor circuit. Furthermore, the freeing 90 of the starting circuit occurs immediately upon the starting of the finder switch, and before another finder switch is brought into operative relation with the starting circuit; 95 so that the starting circuit is available for storing or recording a call during the interval between the starting of one finder switch and the placing of a second finder switch in operative relation with the circuit. 100 Therefore, there may be two calls stored or recorded at the same time, one in the starting circuit, and the other in the distributor circuit. As the transfer of a recorded call from the distributor circuit to 105 the starting circuit immediately upon the starting of the finder switch frees the distributor circuit and makes it immediately responsive to another call, this peculiarity of organization makes the distributor circuit 110 responsive to calls from lines whose terminals are closer together on the distributor switch than would be the case if the freeing of the starting circuit, and the consequent freeing 115 of the distributor circuit were delayed until a second finder switch is brought into operative relation with the starting circuit.

The calling subscriber's line is now connected through the line finder circuit to the other connecting apparatus at the office. 120 This apparatus may be of any type suitable for either an automatic or semi-automatic exchange.

In the particular embodiment shown in Fig. 10, a rotary switch 147 is shown, but it will be evident to anyone skilled in the art 125 that any type of switch can be used for this purpose. The switch shown may be started

and moved in any desirable manner, and when it finds the terminals of an idle selector circuit or an idle connecting circuit, as shown in the particular embodiment of this invention, a circuit will be closed from ground, through the repeating coil winding 148 and the tip side of the line to the terminals and brushes of the rotary switch 147, contacts 1 and 2 of sequence switch spring 109, the tip brush and terminal of the line finder switch and over the tip of the line to the subscriber's station, and back by way of the ring lead of the line, the ring terminal and brush of the line finder switch, contacts 1 and 2 of sequence switch spring 108, the ring brush and terminal of the rotary switch 147, and thence through the relay 160 and the repeating coil winding 149, to battery. This will energize the relay 160 which will attract its armature and close a circuit from ground, through the armature and make contact of this relay, the sleeve terminal and brush of the rotary switch 147, contacts 2 and 3 of sequence switch spring 111, and thence through the operating magnet to the sequence switch 100, to battery. This will move the sequence switch into its fifth position, which is the talking position of the line finder circuit.

30 The calling subscriber may now be connected to the subscriber desired, in any suitable manner. When the conversation is completed and the calling subscriber hangs up his receiver, the circuit containing the supervisory relay 160 is opened and the relay is deenergized. The return to normal of the armature of this relay closes a circuit from ground, through the armature and break contact, the terminal and brush of the rotary switch 147, contacts 4 and 3 of sequence switch 111, and the operating magnet of sequence switch 100 to battery. The sequence switch 100 will consequently move out of its fifth position and into its eighteenth position. When the sequence switch reaches its eighteenth position a circuit is closed from ground, through contacts 2 and 1 of sequence switch spring 112, and the power controlling magnet 53 to battery.

40 Magnet 53 will consequently attract its armature which will cause the idler pulley 54 to make contact with the bar 51 which in turn will contact with the power roller 44, and consequently the brush rod will start to return to normal. Just after the brushes leave the last terminal of the contact bank, the commutator brush 59 will close a circuit from ground, through the commutator segment Y, the contacts 3 and 2 of sequence switch spring 113 and the power magnet of sequence switch 100, to battery. The sequence switch 100 will consequently move into its first position. As the brush is re-

turned to its normal position, the resetting finger 95 will ride on the brush-tripping rod 63 and thereby reset the brushes. When the sequence switch is in position 1, all the relays of the line finder circuit are deenergized and the apparatus is back in its normal position, whereas the sequence switch of the second line finder circuit is moved to its second or preselected position.

If, for any reason, the brushes of a line finder circuit should fail to find the terminals of a calling line, and rise to the topmost terminal of the bank, a circuit will be closed immediately after the brushes leave the topmost terminal, from ground through the commutator brushes 58 and 59 in parallel, the commutator segment X, contacts 1 and 4 of sequence switch spring 114 and the power magnet of the sequence switch 100, to battery. As the sequence switch spring 114 is closed in its third and fifth positions, the sequence switch will move into its eighteenth position, and in this movement will restore the line finder brush-rod, as well as all the other apparatus associated with the finder circuits, to normal. This circuit is provided as a precaution to prevent the brushes of a line finder from traveling to the topmost part of the panel, and remaining there without any means for automatically returning the same.

It will be noticed that the circuit which contains the release relay 137 and which is closed by way of the sequence switch spring 117, is multiplied to the sequence switch springs 217, 317, etc., of the various line finder circuits, thus making the release relay 100 common to all the line finder circuits.

Further, should all the line finders become busy at the same time, provisions are made for moving the sequence switch of the finder circuit, which is first released, to the second or preselected position. This circuit may be traced from ground, through contacts 4 and 3 of the sequence switch spring 316, contacts 4 and 3 of sequence switch spring 216, contacts 4 and 3 of sequence switch spring 116, and assuming that the third line finder is the first to return to normal, through contacts 3 and 4 of sequence switch spring 115, contacts 3 and 4 of sequence switch spring 215, contacts 3 and 2 of sequence switch spring 315, and the power magnet of sequence switch 300 to battery. This will move the sequence switch 300 into the second or preselected position. Consequently whenever one or more of the line finder circuits are idle, one of them will be moved to the second or preselected position. The starting lead to the sequence switches of the various line finders is multiplied to contact 4 of sequence switch spring 103, 203, 303, etc., of the various line finder circuits, and therefore when-

ever the starting relay 135 is operated the particular preselected line finder will be started.

The ground which is supplied to lock the relay 143 and furnish the ground for moving the sequence switch of the succeeding line finder circuit into its preselected position, is multiply connected to contact 3 of the sequence switch springs 105, 205, 305, etc., 10 of the various line finder circuits. It will, therefore, be evident, due to this multiple connection, that at any time when a line finder circuit is started and moves into its third position, the ground supplied by the 15 release relay 137 will seek and find the next succeeding idle line finder switch and move the sequence switch of this finder circuit into its second or preselected position.

A special circuit, which serves as a precautionary measure for preventing the starting 20 of two finder circuits, due to special abnormal conditions, will now be described. Thus, if at any time the sequence switch of the first line finder should be in position 2, while 25 the sequence switch of the line finder circuit 2 is going out of position 18 and the sequence switch of the line finder 3 is in position 1, the sequence switches of the line finders 2 and 3 might be moved into the preselected 30 position 2. Thus, these special conditions regarding the positions of the sequence switches of the three line finder circuits will be assumed, and also that the relay 137 has been deenergized. A circuit can then be 35 traced from ground, through the armature 144 of relay 137, contacts 3 and 2 of sequence switch spring 105, the right-hand armature and contact of relay 143, contacts 3 and 2 of sequence switch spring 106, contacts 40 3 and 4 of sequence switch spring 215, contacts 3 and 2 of sequence switch spring 315 and through the sequence switch power magnet 300, to battery.

Therefore, if cam A of sequence switch 45 300 closes before the sequence switch spring 215 opens at contact 4, the sequence switch 300 will be moved into its second position. The circuit just traced will be opened at contact 4 of spring 215 when the sequence 50 switch 200 moves into its first position, and this will close a circuit through the power magnet of sequence switch 200 at contact 2 of sequence switch spring 215, and this sequence switch will also move into 55 its second position. Consequently, when a ground is supplied to the starting circuit by the armature 142 of relay 135, both sequence switches 200 and 300 would move into their third positions and start their line 60 finders. To prevent this condition, the contacts 4 of the sequence switch springs 112, 212, 312, etc., are connected to a common lead, which is likewise connected to contact

2 of the sequence switch springs 103, 203 and 303, etc. Due to this common connection, any sequence switch which is midway between its first and second position will close a circuit from ground to the sequence switch springs 103, 203, 303, etc., if the sequence switch associated with either one of 70 these springs is in its third position, and from there through the relay 143 connected to the finder circuit associated with such sequence switch to battery.

In the conditions which were assumed, the sequence switch of the first line finder circuit is in its third position. Then if it be further assumed that the cam A of sequence switch 300 has closed before the cam 215 of the sequence switch of line finder 2 has 80 moved out of its eighteenth position, it will follow that when the sequence switch 300 is midway between its first and second positions, a circuit will be closed from ground, through contacts 2 and 4 of sequence switch 85 spring 312, contacts 2 and 1 of sequence switch spring 103 and the relay 143, to battery. This will energize relay 143 and the attraction of its right-hand armature will remove the ground connection which 90 would be supplied to the sequence switch 200, by way of the sequence switch spring 106 and the sequence switch spring 215. The relay 143 will lock up over its make contact and right-hand armature, as previously explained, and this locking circuit will not be interrupted until the sequence switch 100 moves out of its third position. The release of this relay, after this sequence switch is moved out of its third position, 100 will not affect the sequence switch 200, as this circuit is then opened at contact 2 of the sequence switch spring 106. Thus the simultaneous movement of the two sequence switches into the second position is prevented.

To prevent the operation of more than one brush-tripping rod during the interval that one finder switch is being elevated, the multiple series circuit, illustrated in Fig. 110 11, is provided. When relay 130 has been energized and locked up, a circuit is completed from the ground on the right-hand armature of this relay, through its left-hand low-wound winding, the armature 131, the 115 coil and the armature 132 of relay 133, the armature 134 of relay 135 and armature 136 of relay 137, to battery. Relay 133 is, therefore, energized and closes a circuit from ground, through its armatures 140 120 and 131, the coil of the relay and its armatures 132 and 141, and the coil of relay 135 and the armature 136 of relay 137, to battery. The closing of this circuit will energize relay 135 and attract its armature 134. 125

The break contacts of the armatures 132

of the relays 133 of the various distributor circuits are wired in multiple and to the break contact of the armature 134 of relay 135. Therefore, whenever the armature 134 of relay 135 is in its normal position, the circuit through relay 133 of any one of the line finder starting circuits can be completed, and this relay, in parallel with the brush-tripping magnet 84, will be operated. However, whenever any one of the relays 133 is operated, a circuit is closed through the relay 135, which opens this circuit at armature 134 until the relay 135 is deenergized. It will be remembered that the deenergization of the relay 135, which is energized in series with the relay 133, depends upon the operation of the release relay 137, and this relay is maintained in its energized condition until the line-finder brush-rod has been elevated above the tripping pawl and is about to start to test the terminals of the line panel bank. At this time the relay 137 is energized and opens the locking circuit containing relay 133, the brush-tripping magnet 84, and relay 135, and thereby again connects the multiple circuit wired to the armatures 132 of the various distributor relays 133 to the armature 134 of relay 135, thus closing the means which serves to energize the brush-tripping magnet and relay 133 of any one of the distributor circuits. The coil of relay 135 is connected to the armature 141 of the first distributor circuit relay 133, and this armature is wired through its back contact to the armature 141 of the next relay 133. This series circuit is continued through the armatures 141 and contacts of all of the relays 133. Consequently, whenever any one of these relays is operated, this series circuit connected to the coil of the relay 135 through the armatures 141 and break contacts of the relays 133, is broken at the particular relay operated. It follows, therefore, that when the circuit of one brush-tripping magnet 84 is closed, the circuits through the brush-tripping magnets of the other distributor circuits are temporarily opened at the armature 141 of one of the relays 133, or the armature 134 of the relay 135, or at both points. This condition is maintained until the brushes of one of the line finders has been tripped and the brush-tripping magnet 84 and the relays 133 and 135 have been deenergized by the operation of the release relay 137.

As the starting condition of the calling line persists up to the moment the calling line is found, and as a second finder switch is put in readiness and made responsive to the starting circuit at an earlier stage in the movement of the finder switch that is hunting for the calling line, provision is

made for depriving the calling line of control over the starting circuit while the calling line is being hunted, and for restoring this control after the calling line is found. This is effected through the agency of the distributor which operates as a timing switch, its rate of rotation being so regulated that the time required for the brushes 30 to 32 to move from terminals 27 to 29 back to these terminals; *i.e.*, to perform a complete rotation, is greater than the maximum time required for a line finder to be started and connect with any line of the group. The result is that until the electrical condition existing on test terminal 29 is changed as a result of the seizure of this line by a line finder, the reenergization of the starting circuit under the control of the calling line is prevented.

Obviously, this invention is not limited to the specific embodiment herein shown and described, but is capable of many variations and applications without departing from its spirit and scope.

What is claimed is:

1. In a telephone system, the combination with a group of telephone lines, a line relay, a call finder switch for connecting said line relay with said telephone lines one after another in rapid succession, a locking relay under the control of the line relay, and a line finder switch set into operation through the actuation of said locking relay.
2. In a telephone system, the combination with a group of telephone lines, a line relay, means for associating said line relay with the individual lines of said group one after another in rapid succession, a second relay operated under the control of the line relay but not responsive to the deenergization of said line relay, a line finder switch, and a starter circuit therefor controlled by the actuation of said second relay.
3. In a telephone system, the combination with a group of telephone lines, of a continuously rotating call finder switch adapted to make connections with the limbs of the telephone line one after another in rapid succession, a source of current, a line relay common to the lines of said group and adapted to be included with said source of current in the temporarily established connection with each of said telephone lines and momentarily actuated over each telephone line with which it is connected if the telephone line is closed at the substation, a second relay responsive to the energization of the line relay but irresponsive to the deenergization of said line relay, and a line finder switch started into operation by the actuation of said second relay.
4. In a telephone system, the combination with a group of telephone lines, a line finder switch having banked contacts in which said

- lines terminate, a call finder switch having banked contacts in which said lines terminate, a test conductor for each line terminating in a contact in each of said switches, three brushes for each of said switches, two registering with the contacts connected with the limbs of the telephone line and the third with the contact connected with the test conductor, a relay and source of current in circuit with the test brush of the call finder adapted to be actuated whenever a connection is established with a telephone line with which no other connection is at that time established, a line relay and source of current adapted to be connected in a bridge of a telephone line through contacts of the first-named relay whenever the first-named relay is actuated, said line finder switch being set into operation by the actuation of said line relay. 65
5. In a telephone system, the combination with a group of telephone lines, a line finder switch at the central office having passive contacts in which the ends of said telephone lines terminate, an additional test contact for each of said telephone lines, coöperating traveling contacts adapted to register with the passive contacts of various lines one after another, a pair of test relays, one having its coil connected with the traveling contact registering with the test contacts of the various lines and the other having its coil connected with the brushes registering with the line contacts of the various lines, means on the test conductor of each line for completing an actuating circuit for the first test relay when the traveling contacts register with the line with which no other connection has been established at the central office, means for closing the circuit of the second test relay over a telephone line closed at the subscriber's station, and switching circuits controlled by the operation of the second test relay. 70
6. In a telephone system, the combination with a group of telephone lines, of a plurality of passive contacts at the central office of the system on which the limbs of said lines terminate, an additional test contact at the central office for each of said telephone lines, means to test the test contact of said line to determine whether or not a connection has been established with said line at the central office, and means actuated if no connection has been established with said line at the central office for making a second test to determine whether or not the line is closed at the substation. 75
7. In a telephone system, the combination with a plurality of telephone lines, a group of contacts for each line and a plurality of switches to which said contacts are multiplied, a group of traveling contacts for each switch adapted to register with the contacts of said lines one after another, a primary and a secondary test relay for each group of traveling contacts, and means in one switch coöperating with the primary test relay of another switch to prevent the secondary test relay of the latter switch from being connected with its traveling contacts for testing purposes. 80
8. In a telephone system, the combination with a plurality of telephone lines, a test and a pair of talking contacts for said line multiplied to a plurality of switching positions, a primary test relay at one of said positions for testing the busy or idle condition of the multiple test contact of said line, a secondary test relay controlled by said primary test relay and adapted to test the calling or non-calling condition of said line, and means at said multiple switching positions to so control the primary test relay as to prevent the secondary test relay from making its test. 85
9. In a telephone system, the combination with a telephone line, of passive switch contacts at the central office upon which said line terminates, a test contact for said line associated with the passive contacts thereof, means to make a double test on the contacts of said line, the first responsive to the non-busy condition of the test contact of the line and the second responsive to current in the line when the limbs are closed at the substation. 90
10. In a telephone system, the combination with a telephone line, of multiple passive terminals for said line at the central office of the system, multiple test terminals for said line, a set of traveling contacts adapted to register with the line and test terminals of the line, a primary test relay connected with one of said traveling contacts, and a secondary test relay adapted to be connected with the other traveling contacts through contacts of the primary test relay whenever a test is made upon a line with which no other connection has been established at the central office. 100
11. In a telephone system, the combination with a telephone line, of multiple passive terminals for said line at the central office of the system, multiple test terminals for said line, a set of traveling contacts adapted to register with the line and test terminals of the line, a primary test relay connected with one of said traveling contacts, a secondary test relay, and contacts of the primary test relay for preventing the connection of the secondary test relay with the traveling contacts registering with the passive contacts connected with the limbs of the telephone line whenever another connection has been established with the limbs of said line at another point at the central office. 115
12. In a telephone testing system, groups 120
13. In a telephone testing system, groups 125

- of passive terminals to be tested, traveling terminals adapted to register with said passive terminals, a primary test relay, a secondary test relay having its circuit under 5 the control of the primary test relay, and means to control the circuit of the first test relay through one of the contacts of said group to either prevent or permit the second test relay to test another contact of said 10 group.
13. In a telephone system, the combination with a group of telephone lines, a call 20 finder, a line finder switch, a starting circuit for said finder switch, means controlled by the call finder for recording a call in 15 said starting circuit, and means to obliterate said record when the line finder starts to hunt for the calling line.
14. In a telephone system, the combination with a group of telephone lines, a line 25 relay, a call finder for connecting said line relay with said telephone lines one after another in rapid succession, a line finder switch, a starting circuit for said line finder switch, means controlled by said call finder for closing said starting circuit, and means to open said starting circuit when the line 30 finder switch begins to hunt for the terminals of the calling line.
15. In a telephone system, the combination with a group of telephone lines, of a call 35 finder, line finder switches, a starting circuit for said line finder switches, means under the control of the call finder for closing said starting circuit, means to open said starting circuit when one of the line finder switches starts to hunt for the terminals of a calling line and to associate another line 40 finder switch with said starting circuit.
16. In a telephone system, a plurality of 45 automatic switches, means for preselecting one of said switches, means actuated by the calling subscriber for starting said switch, means controlled by said switch for restoring said first means and for preselecting a second switch, and means operated to actuate each one of said plurality of automatic switches before said first preselected automatic switch is again actuated.
17. In a telephone system, a plurality of 50 line finders, means for preselecting one of said line finders, means operated by a calling line for starting said line finder, means controlled by said line finder for restoring said first means and for preselecting a second line finder, and means operated to actuate each one of said plurality of line finders before said first preselected line finder is again actuated.
18. The combination with a plurality of 55 telephone lines divided into groups, of a finder switch adapted for group and individual line selection, a group relay for each group adapted to control the group selecting 60 operation of said finder switch, a holding circuit for each of said group relays, initial energizing circuits for said group relays, a common branch for said circuits, and a switch operated by any line of the group in calling for closing the initial energizing circuit to the corresponding group relay and disconnecting the relays of the succeeding groups from said common branch. 70
19. The combination with a plurality of 75 lines arranged in groups, of a finder switch adapted for group and individual line selection, a relay for each group adapted to be operated by any line of the group in calling and adapted to control the group selecting operation of said finder switch, a starting relay common to all of said groups, a holding circuit including the winding of said starting relay and adapted to be completed through any operated group relay to maintain its energization, means controlled by 80 said starting relay for starting the movement of said finder switch, and a relay common to said groups and operated by said finder switch at the end of the group selecting operation for rendering ineffective said holding circuit. 85
20. The combination with a plurality of 90 telephone lines arranged in groups, of a finder switch adapted for group and individual line selection, a relay for each group adapted to be operated by any line of the group in calling and to control the group selecting operation of said finder switch, a common holding circuit adapted to be completed through any one of said group relays 95 in its operation, and a relay common to said groups for controlling the continuity of said holding circuit, said common relay being adapted to be operated by said finder switch at the end of its group selecting operation to 100 render said holding circuit ineffective. 105
21. The combination with a plurality of 110 lines arranged in groups, of a finder switch adapted for group and individual line selection, group selecting trip magnets associated with said finder switch, one for each said groups of lines, a starting circuit for said finder switch, a starting relay common to all of said groups for controlling said starting circuit, a divided energizing circuit including one of said trip magnets in each of its branches and including said starting relay in the common portion thereof, means under the control of any line in calling for closing said energizing circuit 115 by way of the branch that leads to the trip magnet of the corresponding group, and means included in the common portion of said energizing circuit and operated at the end of the group selecting operation of said 120 finder switch for rendering ineffective said energizing circuit. 125
22. The combination with a plurality of 125 lines, of a plurality of finder switches for making connection therewith, a starting cir-

- 5 cuit for said finder switches, means under the control of any of said lines in calling for energizing said starting circuit, and means for rendering said starting circuit inaccessible to said calling line for a fixed and arbitrary interval after said circuit has been energized.
- 10 23. The combination with a plurality of lines, of a plurality of finder switches for making connection therewith, means for moving said finder switches, means controlled by any line in calling for making one of said finder switches operative to connect therewith, means adapted thereafter to deprive said calling line of control over any other finder switch, and means operated independent of control by said operated finder switch for restoring the control of said calling line.
- 15 24. The combination with a plurality of lines, of a plurality of finder switches for making connection therewith, means actuated by the initiation of a call for starting a finder switch to make connection with the calling line, means actuated in the starting of said switch for rendering another switch responsive to a calling line, means made operative by the finder switch in completing connection with the calling line for making 25 ineffective the starting condition of said line, and a timing switch made effective at the time of the starting of a finder switch for depriving said calling line of control over said starting means and for restoring 30 control at the expiration of an interval greater than that required for the started finder switch to traverse all the lines of the group.
- 35 25. The combination with a group of telephone lines, of a plurality of finder switches for making connection therewith, a starting circuit for said finder switches energized by any line of the group in calling, said finder switches being adapted to be started 40 in succession by successive energizations of said starting circuit, and a timing switch adapted to disconnect a calling line from the starting circuit at the time of the energization of said circuit and reconnect said line 45 at the expiration of an interval greater than that required for said switch to traverse all the lines of the group.
- 50 26. The combination with a plurality of lines, of a plurality of finder switches for making connection therewith, a starting circuit adapted to be energized by any of said lines in calling and adapted to start one of said switches, means operating to place the next switch under the control of the starting circuit at the outset of movement of said first mentioned switch, and means actuated by said first switch in starting for preventing said calling line from starting said next switch.
- 55 27. The combination with a plurality of lines, of a plurality of finder switches for making connection therewith, a starting circuit adapted when a line calls to start one of said switches, means adapted to place another of said switches under the control 60 of the starting circuit before the first switch has found the calling line, and means actuated by said first switch in starting for preventing said calling line from starting said other switch.
- 65 28. The combination with a plurality of lines, of a starting circuit adapted to be energized by any line in calling, a finder switch adapted to be started by the energization of said circuit when a line calls, a second finder switch adapted to be brought into operative relation with said circuit after said first switch starts and before it finds the calling line, and means actuated by said first switch in starting for depriving 70 said calling line of control over said starting circuit before said second switch is brought into operative relation with said circuit.
- 75 29. The combination with a plurality of lines, of a plurality of finder switches for making connection therewith, a starting circuit with which one of said switches is in operative relation; means actuated by any line in calling for energizing said starting circuit to start said switch, means operating to bring another finder switch into operative relation with said starting circuit at the beginning of movement of said first mentioned switch, and means actuated by said 80 started switch for depriving said calling line of control over said starting circuit before said second switch comes into operative relation with said starting circuit.
- 85 30. The combination with a plurality of lines, of a starting circuit adapted to be made operative by any one of said lines in calling, line finder switches adapted to be brought consecutively under the control of said starting circuit at intervals less than 90 that required for a finder switch to find a calling line, and a device actuated by a started switch and adapted to render a calling line ineffective to energize said starting circuit after said line has energized said circuit to start a finder switch.
- 95 31. The combination with a finder switch adapted for group and individual line selection, of groups of lines extending to groups of stationary terminals on said switch, a group-selection controlling magnet on said switch for each group of terminals, an energizing circuit for each magnet adapted to be closed upon the initiation of a call by any line in the corresponding group, and means 100 under the control of said finder switch for opening said energizing circuit.
- 105 32. In a telephone exchange system, a plurality of switches, each having a plurality of normally inactive brushes and a corre- 110

sponding plurality of groups of stationary contacts arranged to be traversed by said brushes respectively, telephone lines arranged in groups terminating in said groups 5 of contacts, tripping devices for rendering said brushes active, each tripping device being common to a plurality of said switches, and means automatically actuated upon the initiation of a call on any of said lines to 10 operate a tripping device to render active that brush of one of said switches which has access to the terminal of the calling line.

33. In a telephone exchange system, a plurality of longitudinally movable shafts, a 15 plurality of normally inactive brushes, on each of said shafts, groups of contacts arranged to be traversed by said brushes respectively, telephone lines multiply connected to corresponding contacts of said 20 switches, tripping devices for rendering said brushes active, each tripping device being common to all of said switches, and means actuated upon the initiation of a call on any one of said lines to operate that tripping 25 device which is arranged to release the brushes having access to the contact terminals of said calling line.

34. In a telephone exchange system, a plurality of longitudinally movable shafts 30 arranged in substantially parallel relation to each other, a plurality of multiply connected brush sets on each of said shafts, groups of contacts arranged to be traversed by said brushes respectively, telephone lines 35 multiply connected to contacts at said switches, a controlling device for each brush set normally retaining the brushes thereof in inactive position, trip rods extending adjacent to said controlling devices, each trip 40 rod being common to the corresponding controlling devices on a plurality of said switches, and means actuated upon the initiation of a call on one of said lines to operate that tripping device which is associated with the brush sets having access to 45 said calling line.

35. In a telephone exchange system, a group of switches, each having a plurality of normally inactive brush sets and a like 50 plurality of groups of contacts, telephone lines multiply connected to contacts in corresponding groups at said switches, brush tripping devices equal in number to the greatest number of brush sets on any one 55 switch, each tripping device being adapted to cooperate with the correspondingly positioned brush set on any of said switches, and means actuated upon the initiation of a call on any of said lines to operate that tripping 60 device which is arranged to cooperate with the brush sets having access to the contact terminals of said calling line.

36. In a telephone exchange system, a plurality of longitudinally movable brush 65 shafts, each having a like plurality of mul-

tiply connected brush sets, and a like plurality of groups of contacts arranged to be traversed by said brush sets respectively, telephone lines multiply connected to contacts in corresponding groups, a controlling 70 device for each brush set normally maintaining the brushes thereof in inactive position, trip rods equal in number to the number of sets of brushes on any one switch, each trip rod being arranged to cooperate 75 with the correspondingly positioned controlling device on any of said switches, and means automatically actuated upon the initiation of a call on any of said lines to operate that trip rod which is arranged to co- 80 operate with controlling devices of the brush sets which have access to the contact terminals of said calling line.

37. In a telephone exchange system, a plurality of longitudinally movable switch 85 shafts arranged substantially parallel in the same plane, each shaft having a plurality of multiply connected brush sets, groups of contacts each being arranged to be traversed by a different set of brushes, 90 telephone line multiply connected to contacts in corresponding groups, a controlling device for each brush set normally maintaining the brushes thereof in inactive position, trip rods extending at right angles to said 95 shafts but parallel to the plane thereof, said trip rods being equal in number to the greatest number of brushes on any one shaft, means carried by said trip rods arranged to cooperate with the correspondingly positioned controlling devices on any of said 100 switches to release the brushes thereof, and means automatically actuated upon the initiation of a call on any of said lines for operating that trip rod which is arranged to cooperate with the controlling devices of the brush sets having access to the contact terminals of said calling line.

38. In a telephone exchange system, a plurality of subscribers' lines divided into groups, a plurality of switches each having groups of contacts at which said groups of lines respectively terminate, a plurality of normally inactive brush sets on each of 110 said switches, a brush set being provided on each switch for each group of contacts, brush tripping devices one for each group of lines, and means actuated when a call is initiated on any one of said lines for operating a trip- 115 ping device which is arranged to cause the release of the brushes having access to the calling line group.

39. In a telephone exchange system, a plurality of lines divided into groups, switches each having a contact bank divided into sections in which said line groups respectively terminate, brushes on each of said switches one for each section of its contact bank, controlling devices for normally maintaining said brushes in inactive posi- 120 125 130

- tion, brush-tripping devices one for each group of lines, each of said devices being arranged to release a corresponding brush on any of said switches, and means automatically actuated upon initiating a call on any of said lines for operating the tripping device arranged to coöperate with the controlling devices of the brushes having access to the contact terminals of said calling line.
40. The combination with a plurality of lines divided into groups, a finder switch, terminals for each of said lines upon said finder switch, movable brushes for said switch, a brush for each group of line terminals, an extension circuit having multiple connections with said brushes, means for causing the movement of said brushes, means for normally holding each brush out of engagement with the line terminals of the associated group, electromagnetic tripping mechanisms, one being associated with each group of line terminals and adapted when operated to cause the corresponding brush to engage the associated line terminals in the movement of the switch, starting mechanism for starting the movement of said brushes, energizing paths for said starting mechanism and said electromagnetic tripping devices, and means operated by any line in calling for closing said energizing paths to operate the switch starting mechanism and the tripping device of the group in which the calling line is located.
41. The combination with a finder switch having stationary terminals arranged in groups and a movable switch element adapted for group and individual terminal selection, motor mechanism for moving said movable element, a trip magnet on said switch for each of said groups of stationary terminals, said trip magnets being adapted to control the group selecting operation of said movable element, telephone lines extending to said stationary terminals, and means made operative by any line in initiating a call to energize said motor mechanism and the trip magnet of the group in which the calling line terminates.
42. In a telephone exchange system, a plurality of switches each having a plurality of normally inactive brushes and a corresponding plurality of groups of stationary contacts arranged to be traversed by said brushes respectively, telephone lines arranged in groups terminating in said groups of contacts, tripping devices for rendering said brushes active, each tripping device being common to a plurality of said switches, means automatically actuated upon the initiation of a call on any of said lines to operate a tripping device to render active that brush of one of said switches which has access to the terminal of the calling line, and means whereby a single tripping device may remain actuated at a time.
43. In a telephone exchange system, a plurality of switches each having a plurality of normally inactive brushes and a corresponding plurality of groups of stationary contacts arranged to be traversed by said brushes respectively, telephone lines arranged in groups terminating in said groups of contacts, tripping devices for rendering said brushes active, each tripping device being common to a plurality of said switches, means automatically actuated upon the initiation of a call on any of said lines to operate a tripping device to render active that brush of one of said switches which has access to the terminal of the calling line, and means for preventing a plurality of said tripping devices remaining actuated at a time.
44. The combination with a finder switch having a plurality of groups of stationary terminals and a movable element provided with a brush for each group of stationary terminals, of telephone lines connected with said stationary terminals, an extension circuit having multiple connection with the brushes of said movable element, mechanism for causing the movement of said movable element, a tripping device for each of said brushes adapted when operated to cause the brush in its movement to engage the stationary terminals of the corresponding groups, an energizing circuit for said moving mechanism and the tripping device of the corresponding group, and means made operative in the operation of the switching mechanism of each of said groups to prevent the operation of the switching mechanism of any other group.
45. The combination with a plurality of telephone lines divided into groups, of an extension circuit common thereto, a finder switch adapted to connect said extension circuit with any line in any of said groups, mechanism for causing the movement of said finder switch, a group identifying device on said finder switch for each of said groups of lines, means made operative in the initiation of a call by any of said lines for operating said switch moving mechanism and the identifying device corresponding with the group in which the calling line is located, and means made active in the operation of any of said group identifying devices for rendering the identifying devices of the other groups inoperative.
46. The combination with a finder switch having a plurality of stationary terminals arranged in groups and a multiple brush movable element with a normally inactive brush for each of said groups of stationary terminals, of a trip magnet on said switch

for each of said brushes, said magnet being adapted when operated to make said brush active, motor mechanism for said movable element, means for causing the actuation of said motor mechanism and at the same time operating one of the aforesaid trip magnets to render the corresponding brush active, and means actuated in the operation of any one of said trip magnets for rendering the other magnets inoperative.

47. The combination with a finder switch having a plurality of stationary terminals arranged in groups and a multiple brush movable element with a normally inactive brush for each of said groups of stationary terminals, telephone lines connected with said stationary terminals, an extension circuit connected with the multiple brushes of said movable element, electromagnetic mechanisms, one for each of said brushes adapted when operated to make the corresponding brush active, electrically controlled motor mechanism for said movable element, a switch made operative in the initiation of a call by any of said lines for rendering operative said motor mechanism and said electromagnetic mechanism associated with the group in which the calling line is located, and means made operative in the closure of any one of said switches for rendering ineffective the other switches.

48. In a telephone system, the combination with a multiple brush line finder, of electromagnetic tripping devices, one for each set of brushes, an energizing circuit for each of said devices, and means actuated in the operation of any of said energizing circuits for rendering the other circuits inoperative.

49. The combination with a finder switch adapted for group and individual terminal selection, of groups of lines extending to groups of stationary terminals on said switch, a device associated with each stationary terminal group for controlling the group selecting operation of said switch, an electromagnet for each of said devices adapted to cause the operation thereof, an initial energizing path for each electromagnet controlled by the lines of the corresponding group, means operated in the operation of any of said devices for rendering said initial energizing paths of all said groups ineffective, and means made operative after the switch has performed its group selection for restoring the effectiveness of said energizing paths.

50. In a telephone system, the combination with a multiple brush line finder, of electromagnetic tripping devices, one for each brush, an energizing circuit for each of said devices, means for closing each energizing circuit, means actuated in the closure of any of said energizing circuits for rendering the other circuits inoperative, and means con-

trolled in the movement of said line finder for opening the closed energizing circuit.

51. In a telephone system, the combination with a multiple brush finder switch, of telephone lines arranged in groups and connected with corresponding groups of terminals on said finder switch, an electromagnetic tripping device for each brush of said switch, a relay for each of said groups of lines, an energizing circuit for said relay and the corresponding brush tripping device closed in the initiation of a call by any line in the corresponding group, means associated with each of said group relays and actuated in the operation of said relays for rendering said energizing circuits of the other group relays inoperative, and means actuated in the movement of said finder switch after the completion of the tripping operation for restoring said energizing circuits to their normal condition.

52. The combination with a plurality of lines, of a plurality of finder switches for making connection therewith, means for moving said finder switches, means controlled by any line in calling for making a moving finder switch operative to connect therewith, and means adapted thereafter to deprive said calling line of control over any finder switch until after said line is found.

53. In combination, a line, a plurality of finder switches, means provided for each of said switches for causing it to hunt for said line, and means for preventing said switches from hunting for said line after one of said switches has been started.

54. The combination with a switch having a plurality of groups of terminals and a corresponding plurality of normally inactive brushes, of a magnet for each brush, means controlled by each magnet for making the corresponding brush active, and selecting apparatus independent of said switch for causing the operation of any desired one of said magnets and preventing the operation of the others.

55. The combination with a switch having a plurality of sets of terminals and a corresponding plurality of sets of brushes, a latch for each set of brushes for holding the same normally inoperative, a tripping device for each latch, the latches and their respective tripping devices being so arranged as to come into operable relation simultaneously in the movement of the switch, means for operating any of said tripping devices, and means actuated in the operation of any tripping device for rendering said other devices inoperative.

56. The combination with a switch having a plurality of normally inactive sets of brushes, a corresponding plurality of devices simultaneously operable in the movement of the switch, each of said devices being

adapted in its operation to render its respective set of brushes active, and selecting means independent of said switch for causing the operation of one of said devices and preventing the operation of the others.

57. In a telephone system, the combination with a plurality of lines, of a distributor switch for testing the terminals of said lines in rapid succession, a plurality of finder switches for making connection with said lines, a starting circuit for said finder switches, means for energizing said starting circuit when said distributor switch encounters the terminal of a calling line, means for bringing said finder switches successively into operative relation with said starting circuit, and means associated with said starting circuit for storing a call when the rate at which terminals of calling lines are encountered exceeds the rate at which successive finder switches are brought into operative relation with said starting switches.

58. In a telephone system, the combination with a plurality of telephone lines, of a distributor switch for testing the terminals of said lines in rapid succession, a plurality of finder switches for making connection with said lines, and operative connections between said distributor switch and said finder switches, said operative connections including a recording mechanism for recording a plurality of calls when said distributor switch engages the terminals of a plurality of calling lines in a brief interval of time, and means controlled by said recording mechanism for causing each of said recorded calls to start one of said finder switches and place another of said switches in readiness to be started.

59. In a telephone system, the combination with a group of telephone lines, of a distributor switch, a circuit therefor, finder switches, a starting circuit for starting the movement of said finder switches, means controlled by said distributor switch for recording calls from a plurality of calling lines in said distributor circuit and said starting circuit, and means actuated as each finder switch is started for obliterating the record of one of said calls and bringing another finder switch into operative relation with said starting circuit.

60. The combination with a plurality of telephone lines, of a distributor switch for testing the terminals of said lines in rapid succession, a distributor circuit responsive to the engagement of said switch with the terminals of a calling line, a plurality of finder switches for making connection with said lines, a starting circuit with which one of said finder switches is normally connected, means actuated in the starting of said finder switch for disconnecting the started switch from the starting circuit and connecting a

second finder switch thereto, means under the control of said distributor circuit for energizing said starting circuit to start a finder switch, and means for recording a call in said distributor circuit while said starting circuit is energized.

61. The combination with a plurality of telephone lines, of a distributor switch for testing the terminals of said lines in rapid succession, a distributor circuit responsive to the engagement of said switch with the terminals of a calling line, a plurality of finder switches for making connection with said lines, a starting circuit with which one of said finder switches is normally connected, means actuated in the starting of said finder switch for disconnecting the started switch from the starting circuit and connecting a second finder switch thereto, means under the control of said distributor circuit for energizing said starting circuit to start a finder switch, and means for recording a call in said starting circuit while said second finder switch is being brought into operative relation with said starting circuit.

62. The combination with a plurality of telephone lines, of a distributor switch for making connection with the terminals of said lines one after another in rapid succession, a distributor circuit responsive to the engagement of said switch with the terminals of a calling line, a starting circuit responsive to the response of said distributor circuit, a plurality of finder switches one of which is normally under the control of said starting circuit, means actuated in the starting of said finder switch by the response of said starting circuit for disconnecting the started switch and placing a second finder switch under the control of said circuit, means for storing a call in said distributor circuit while said starting circuit is engaged, and means for storing a fall in said starting circuit while said second finder switch is being brought into operative relation with said starting circuit.

63. The combination with a starting circuit and finder switches controlled thereby, of a plurality of lines, means actuated by any of said lines in calling to cause the closure of said circuit and remove the same from the control of said lines, means operated by the closure of said circuit for starting a finder switch, means operated in the starting of said finder switch for opening said starting circuit and placing a second finder switch in operative relation therewith, and means acting independently of the placing of said second finder switch in operative relation with said starting circuit for restoring said circuit to the control of said lines.

64. The combination with a plurality of lines, of a plurality of finder switches for making connection therewith, a starting cir-

cuit, means actuated by any of said lines in calling for energizing said circuit to start one of said switches, means actuated at the outset of movement of said switch for de-
5 energizing said starting circuit and placing a second switch in operative relation therewith, and means acting prior to the placing
of said second switch in operative relation

with said starting circuit for rendering said circuit again responsive to calling lines.

In witness whereof, I hereunto subscribe my name this 22 day of August, A. D. 1914.

SAMUEL B. WILLIAMS, JR.
